Henry Hubbard James Inventor
By his Attorney D. P. Preble Jr.

UNITED STATES PATENT OFFICE.

HENRY HURLBUT JAMES, OF NEW YORK, N. Y.

CIGAR-CUTTING PAPER-KNIFE.

No. 824,023.

Specification of Letters Patent.

Patented June 19, 1906.

Application filed January 15, 1903. Serial No. 139,101.

To all whom it may concern:

Be it known that I, HENRY HURLBUT JAMES, a citizen of the United States, and a resident of the city, county, and State of New York, have invented a certain new and useful Cigar-Cutting Tool, of which the following is a specification.

The object of my invention is to provide a combination-tool, more particularly intended for smokers' use, and which combines in one easily-handled structure a device for cutting the end of a cigar, a device for opening the cigar-box, and a device adapted to serve as a hammer. In addition to these purposes this structure can be used for opening envelops, cutting magazines and other papers, and also as a seal, and I therefore call it a "cigar-cutting paper-knife."

One form of my invention is shown in the accompanying drawings, in which—

Figure 1 is a top plan with the cigar-cutter closed. Fig. 2 is a top plan, partly broken away, showing the cigar-cutter open. Fig. 3 is a top view, partly in section and partly in elevation. Fig. 4 is an edgewise view.

Same letters indicate similar parts in the different drawings.

A is the body or handle. B is the blade. C is the hammer-surface. D is the cigar-cutter, which is adapted to play in the hollow handle A. This structure is preferably made of metal, with the blade, handle, and hammer formed as one solid piece. The blade is preferably thinner at the edges to be used as a cutter for magazines, &c., and should be strong enough to force the lid of the cigar-box open by lifting the fastening-nail. The hammer end may be used for striking either with the edge or end. The cigar-cutter D consists of a finger a, mounted upon a pivot

b, set in the hollow handle A. This finger carries the triangular blade c and at the forward end is provided with a notch. A spring e is secured to the handle A at the forward end of the longitudinal slot f, in which the finger plays. The function of this spring is to retain the finger normally closed in the slot f. When the finger is released by pressure of the thumb on the spring e, it is thrown out of the slot, as shown in the Figs. 2 and 3, by the coiled spring g, which is attached to the handle A and compressed by the finger when closed. For convenience in closing the finger is provided with a pressure-surface or button h. The hole or opening i is provided through the top of the hollow handle directly over the path of the cutting-blade c, so that the end of a cigar may be inserted through said hole in position to be cut by said blade.

I claim—

A cigar-cutting paper-knife comprising a solid body composed of a single piece of metal having a longitudinal recess near one end, and an extended handle tapering outwardly at the opposite end; a finger pivoted in said recess having a notch in its forward end, a pressure-surface near said end, a cigar-end cutter mounted on said finger, a spring to hold said finger outwardly, and a spring-catch at one end of the recess to engage said finger when closed, said pressure-surface and spring-catch being disposed in position to be actuated by the holder's thumb; a side aperture connecting with said recess whereat to enter a cigar end to be cut, and an exit-opening provided below the cutter.

HENRY HURLBUT JAMES.
